CLAIM

The ornamental design for a slotted angle stanchion, as shown and described.

DESCRIPTION

FIG. 1 is a right, front perspective view of a slotted angle stanchion in accordance with the present design;

FIG. 2 is a left, back perspective view thereof;

FIG. 3 is a front view thereof;

FIG. 4 is a right side view thereof;

FIG. 5 is a left side view thereof;

FIG. 6 is a back view thereof;

FIG. 7 is a top view thereof;

FIG. 8 is a bottom view thereof; and,

FIG. 9 is an enlarged, close-up top perspective view of a portion of the post component of the slotted angle stanchion.

1 Claim, 9 Drawing Sheets
